SHIRT HOLDER

Frank Jones, Toronto, Ontario, Canada

Application December 21, 1936, Serial No. 116,902

3 Claims. (Cl. 2—117)

The principal objects of this invention are to overcome the discomfort, inconvenience and unsightliness of men's apparel in having the shirt front creased or pushed upwardly under the vest so that it becomes not only uncomfortable but unsightly and to provide on men's shirts a very simple and inexpensive fastener which may be optionally utilized and which will be inconspicuous when used or entirely hidden when not in use as a fastening element.

The principal feature of the invention consists in securing on the inner side of the placket of a shirt front a looped elastic member adapted to be extended through a button-hole of a shirt and to be anchored upon a button of the trousers.

In the accompanying drawing, Figure 1 is a perspective view of a shirt showing the front placket open disclosing the arrangement on the inner side thereof of my improved fastener.

Figure 2 is a full size elevational detail showing a portion of the waistband of the trousers and the placket of the shirt in wearing position, the improved fastener member being shown in dotted lines as when not in use.

Figure 3 is an elevational view similar to Figure 2 showing the fastener member extended through a button-hole of the shirt placket and anchored upon the upper trouser button.

Figure 4 is an elevational view from the inside of the placket showing the elastic fastening loop and the manner of securing same in position.

The comfort and appearance of men's wearing apparel is almost universally detrimentally affected when wearing a vest by the front of the shirt working up through the physical movements of the body in changing from a standing to a sitting position and it is extremely desirable that some provision be made for holding the shirt from this upward creeping action. This has been accomplished in the present invention in a very simple and desirable manner.

In the usual construction of a soft front shirt the placket facing 1 is formed of a strip of fabric having the edges turned in and stitched to the hem edge of the shirt body 2 with two longitudinal lines of stitching 3 and 4 spaced inwardly from each longitudinal edge of the facing.

Buttonholes 5 are spaced throughout the length of the facing 1 midway between the rows of stitching 3 and 4.

On the inner side of the shirt at a short distance below one of the lower button-holes is se-

cured a loop 6 formed of a length of elastic cord preferably of the flat multiple strand type, the ends 7 of which are sewn diagonally across by the stitching 3 and 4. The doubled portion of the loop is suspended centrally of the width of the placket facing and the lower end thereof is formed into a closed loop by a binding member 8.

This loop member is adapted to be passed through the button-hole in the placket immediately therebelow and stretched downwardly to embrace the top button 9 of the trousers 10. This flat elastic loop when placed over the trouser button fits flatly over the top of the trouser band and thus holds the trouser band close into the shirt and the elastic tension of the stretched loop member 6 exerts a constant downward pull upon the placket facing so that when the person sits down, no matter how many times the operation may be repeated or how he may shift his posture in the chair in which he is sitting, the elastic tension of the loop will keep the shirt from being worked upwardly so that there will not be an excess amount of material worked up toward the collar.

It is found in practice that a fastening loop such as described maintains the shirt front in a proper relation at all times which not only enhances the appearance, but ensures comfort.

The device is extremely simple and inexpensive and will be always available for use.

What I claim as my invention is:—

1. In a shirt having a placket front provided with button-holes and parallel rows of stitches extending either side of said holes, an elastic fastener element arranged upon the inner side of the placket and secured by said parallel rows of stitches and having a free end adapted to be extended through one of the button-holes and secured to the trousers.

2. A shirt having a placket facing secured by dual rows of stitches to the shirt body, and a loop of elastic material having its ends secured on the inner side of the shirt by said rows of stitches with the loop arranged between the rows of stitching.

3. A shirt having a placket facing secured by a pair of vertical spaced apart rows of stitches, a length of elastic cord formed into a loop and having its ends caught and held by the said spaced rows of stitches extending diagonally thereacross.

FRANK JONES.
